CLAIM

The ornamental design for a bread box, as shown and described.

DESCRIPTION

FIG. 1 is a front perspective view of a bread box showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a rear perspective view thereof;

FIG. 8 is a front perspective view thereof with doors in an opened configuration;

FIG. 9 is a front perspective view thereof with a drawer in an opened configuration;

FIG. 10 is a front perspective view thereof with the drawer having two partitions; and,

FIG. 11 is a front perspective view thereof with the drawer having four partitions.

A bottom plan view of the bread box is not provided as it does not contain any ornamentality.

1 Claim, 11 Drawing Sheets
